[57] CLAIM

The ornamental design for a pedestal desk, as shown and
described.

DESCRIPTION

FIG. 1 is a perspective view taken from the left-front
corner and from above of a pedestal desk showing my
new design;

FIG. 2 is an elevational view taken from the right side
hereof, and of the alternate embodiment of FIG. 6;
FIG. 3 is a top view thereof, and of the alternate em-
bodiment of FIG. 6;

FIG. 4 is a bottom view thereof and of the alternate
embodiment of FIG. 6;

FIG. 5 is a rear view thereof, and of the alternate em-
bodiment of FIG. 6; and

FIG. 6 is a perspective view taken from the left-front
corner and from above of a pedestal desk showing an
alternate embodiment thereof.
